UNITED STATES PATENT OFFICE.

WILLIAM H. EVERSON, OF CLEVELAND, OHIO, ASSIGNOR OF ONE-THIRD TO WILLIAM E. PEASE AND ONE-THIRD TO NOAH H. SULOFF, OF CLEVELAND, OHIO.

CRIBBING FOR SHORE-PROTECTING SYSTEMS.

Original application filed January 3, 1922, Serial No. 526,548. Divided and this application filed August 7, 1922. Serial No. 580,046.

To all whom it may concern:

Be it known that I, WILLIAM H. EVERSON, a citizen of the United States, resident of Cleveland, county of Cuyahoga, and State of Ohio, have invented new and useful Improvements in Cribbing for Shore-Protecting Systems, of which the following is a specification, the principle of the invention being herein explained and the best mode in 10 which I have contemplated applying that principle, so as to distinguish it from other inventions.

This application constitutes a division of my pending application Serial No. 526,548, 15 shore protecting systems, filed January 3, 1922.

My present invention relates to a cribbing structure for use in shore protecting systems, breakwater jetties or the like, its object being to provide a cribbing or crib work structure which will be economical of construction and efficient in the performance 20 of its function.

The said invention consists of means hereinafter fully described and particularly set forth in the claims.

More specifically, my invention consists of a cribbing or crib work structure so arranged as to present a solid face to incoming waves in connection with means for largely destroying the force of such waves before they strike said face. The said invention furthermore consists of a cribbing or crib work structure built of cross courses 30 of beams, preferably reinforced concrete H beams.

The annexed drawings and the following description set forth in detail certain means embodying my invention, the disclosed 40 means, however, constituting but one of the various mechanical forms in which the principle of the invention may be employed.

In said annexed drawings:

Fig. 1 represents a plan of one of the cribbing breakwater or jetty units.

Fig. 2 represents a perspective view, upon an enlarged scale, showing the lower portion of the seaward corner of one of the cribbing or crib work units.

Fig. 3 represents a rear elevation of one 50 of the units viewed from the plane indicated by line III—III, in Fig. 1.

Fig. 4 represents an oblique side elevation of one of the units, viewed from the plane indicated by line IV—IV in Fig. 1. 55

Fig. 5 represents a perspective view, upon an enlarged scale, of a lower rear corner of one of the cribbing or crib work units as viewed from the exterior.

Figs. 6, 7 and 8 represent respectively, a 60 side elevation, plan and section of one of the concrete H beams used in the cribbing or crib work units.

Figs. 9, 10 and 11 represent respectively, an end elevation, a side elevation and a top 65 plan, of the header block which is used to reinforce the open crib work intermediately of its corners.

Figs. 12 and 13 represent respectively, a 70 side and end elevation, of a positioner interposed between superposed beams and the solid wall of the cribbing or crib work.

Figs. 14 and 15 represent a side elevation and transverse section respectively, of one of the corner base beams. 75

Figs. 16 and 17 represent respectively, a plan and a side elevation of an interlocker for the cross beams in the cribbing or crib work.

Fig. 18 represents a section taken upon 80 the plane indicated by line XVIII—XVIII of Fig. 16.

The illustrated embodiment of my invention comprises a structure built up of reinforced concrete H beams 9 which form two 85 converging open work combing walls 7 and 8 and a solid rear wall 6. In the solid rear wall 6 the beams 9 are placed one on top of the other with their webs horizontal and the flanges of one resting on the flanges of 90 the beam therebeneath, and with the ends of alternate beams staggered to provide spaces for the ends of the beams of the wave combing walls as clearly shown in Figs. 3 and 5. To interlock the superposed beams 95 of the wall 6, short positioner blocks 13 of reinforced concrete which fit within the opposed channels of the superposed beams are

interposed at suitable intervals between each pair of superposed beams from the bottom to the top of the wall 6. The beams of the side walls are positioned with their webs 5 horizontal and with their rear ends positioned between the ends of alternate beams in the wall 6 in spaces provided by the staggered arrangement of the beams in said wall. The beams of one of the wave combing walls are thus positioned in the same plane as alternate beams in the wall 6 and the beams of the other wave combing wall are positioned in the plane of the alternate beams positioned between the beams of the 10 first wave combing wall. The two courses of spaced beams forming the wave combing walls intersect at the forward ends of the beams with the beams of one wall alternating with those of the other wall. The 15 beams of the wave combing walls 7 and 8 are interlocked with each other at the intersection of said walls and with the beams of the solid wall 6 by means of interlockers consisting of reinforced concrete X blocks 20 14 having upper and lower crossed legs 15 and 16 adapted to fit within the channels of the superposed crossed beams. The corners of the triangular crib-work units rest on short base beams 17 which are short sections 25 of reinforced concrete H beams of the same size as the beams 9. The base beams 17 are arranged with their webs horizontal beneath the lowermost beam at each of the corners and interlocked with the H beam resting 30 directly thereon by means of interlockers 14. Each of the beams 9 has an aperture 35 18 centrally through the web adjacent each end thereof and each of the interlockers 14 has an axial aperture 20 which is positioned 40 in registry with the apertures 18 of the H beams which it engages. The base beam 17 has a central aperture 21 which registers with the aperture 20 of its interlocker 14. A tie bolt 22 extends vertically through the 45 aperture 18 of the beams, 20 of the interlockers and 21 of the base beam at each of the three corners of the unit. The ends of the tie bolts 22 are threaded to receive nuts 23 which are tightened against anchor plates 50 24 lying against the webs of the uppermost beams and of the base beams 17. The location of the ends of the tie bolts in the channels of the uppermost and lowermost beams makes it convenient to cover the projecting 55 ends thereof with concrete. The entire bolt together with the projecting ends and anchor plates should be grouted in, preferably with a mixture of one part Portland cement to two parts of clean fine sand.

60 To provide the necessary support for the intermediate portions of the spaced H beams in the open-work walls and to more rigidly interlock the beams of said walls, I have provided headers, comprising short H shaped reinforced concrete blocks 25 having integral

lugs 26 and 27 extending transversely across the upper and lower faces thereof and adapted to fit within the opposed channels of the spaced beams. The headers 25 serve to hold the side wall beams in vertical alignment and to support the beams intermediate their ends.

The cribwork units 4 are preferably set upon brush mats 28 as shown in Figs. 2, 3 and 4. The short supporting beams 17 at the corners of the structure sink into the matting or soil and serve to anchor the units in position. If found desirable the units may be weighted down by piling rip rap stone or sacked cement within them. Such material, however, should not be piled high enough against the open-work walls 7 and 8 to interfere with the wave combing action thereof.

By means of the above described structure, wherein two converging open-work combing walls are provided, together with a rear solid wall, the force of the waves is broken by said combing before it reaches such solid wall, thereby permitting the structure to more efficiently withstand forces of such waves.

An advantage of the triangular construction of the breakwater units is that the apices of these triangular units on the seaward side serve to break up floating cakes of ice and prevent damage to the breakwater wall.

What I claim is:

1. A wave resisting structure, comprising crossed concrete H beams, said beams being arranged with the webs thereof horizontal; an interlocker between the superposed beams at the intersection thereof, comprising a block having integral upper and lower crossed portions adapted to fit within the channels of said superposed crossed beams, and means extending substantially from top to bottom of the structure and passing in common through the beams and blocks.

2. A wave resisting structure, comprising opposed courses of concrete H beams, the beams in each course being disposed in vertical alignment and positioned with their webs horizontal; interlockers between the superposed beams of the courses at the intersection thereof comprising blocks having integral upper and lower crossed portions adapted to fit within the channels of superposed crossed beams; and tie bolts extending from the top to bottom of crossing courses of beams and passing through the webs of said beams and said interlockers.

3. A wave resisting structure, comprising crossed courses of concrete H beams, said beams being arranged with the webs thereof horizontal; interlockers between the superposed beams at the intersections thereof comprising blocks having integral upper and lower crossed portions adapted to fit within the channels of said superposed crossed

- beams; and a tie bolt passing through the webs of said beams and said interlockers, said tie bolt being entirely embedded in concrete.
4. A wave resisting structure comprising spaced solid walls; and cribwork wave combing structures extending outwardly from said walls, some of the beams of said cribwork projecting through said walls into the space between said walls.
5. A wave resisting unit, comprising a triangular structure having one wall solid and the other two walls of open-work construction.
6. A wave resisting unit, comprising a triangular cribwork of crossed beams, one wall thereof being solid and the other two walls each consisting of a course of vertically spaced beams extending from adjacent the ends of said solid wall, the two courses intersecting adjacent the outer ends thereof.
7. A wave resisting unit comprising a triangular cribwork of crossed beams, one wall thereof being solid and the other two walls each consisting of a course of vertically spaced beams interlocked at one end thereof with said solid wall adjacent the ends thereof, said courses intersecting adjacent the outer ends thereof and interlocked at the crossing points of the beams thereof.
8. In a wave resisting unit, the combination with a solid wall; of an open cribwork wave combing structure consisting of crossed courses of beams, the ends of the beams in certain of said courses being rigidly interlocked with said wall; means for rigidly interlocking said courses together at their intersections; and headers interposed between the spaced beams of each course to reinforce the open portions of said cribwork.
9. A wave resisting unit, comprising a triangular cribwork of crossed beams of substantially equal length, one wall of said cribwork consisting of beams laid one on top of another to form a solid wall, said beams in said solid wall being laid with the ends of alternate beams projecting beyond intermediate beams to provide spaces for receiving the beams of the other two walls, said last mentioned walls each consisting of a course of beams spaced vertically apart a distance equal to the thickness of a beam, the rear end of said beam being positioned in the said spaces provided at the ends of said solid wall, said two courses of beams intersecting adjacent the forward ends thereof, the beams of one course alternating with the beams of the other course; means for interlocking said forwardly extending beams to said wall and means for interlocking said courses of beams at their outer ends.
10. A wave resisting unit, comprising a triangular cribwork of crossed beams, one wall of said cribwork consisting of beams of equal length laid one on top of the other with the ends of alternate beams projecting beyond the ends of intermediate beams, the other two walls of said cribwork consisting of vertically spaced beams having their rear ends positioned between projecting ends of alternate beams in said solid wall and their forward ends crossed; short supporting beams at each of the bottom corners of said cribwork; and tie bolts extending from the top to the bottom of said structure and passing through the crossed superposed beams at said corners and anchored to said supporting beams.
11. A wave resisting unit comprising a triangular cribwork of crossed concrete H-beams of substantially equal length, one wall of the cribwork being formed of superposed beams laid one on top of the other with the flanges thereof edge to edge and arranged in staggered relation, the ends of alternate beams extending beyond the ends of intermediate beams, the other two walls consisting of vertically spaced beams interlocked at their ends with the projecting ends of the beams of said solid wall, the forward ends of the spaced beams of one of said walls fitting between and interlocked with the spaced beams of the other wall; means for interlocking the superposed beams of each of said walls intermediate the ends thereof.
12. In a wave resisting unit, the combination with a solid wall; of an open cribwork of crossed courses of vertically spaced concrete H-beams arranged with the webs thereof vertical, certain of said beams being rigidly interlocked with said wall; means for rigidly interlocking said courses at their intersections; and header blocks having end portions fitting within opposed channels of said vertically spaced beams and an intermediate wider portion fitting between the opposed flanges of said spaced beams to form intermediate reinforcing and interlocking means for said courses.
13. A wave resisting unit, comprising a solid wall consisting of concrete H beams, superposed with their flanges edge to edge, positioners interposed between said superposed beams and fitting within the opposed channels thereof; courses of concrete H beams extending outwardly from said wall with the inner ends of the beams of each course interposed between alternate beams of said wall, the beams of said wall being arranged in staggered relation to provide openings to receive said outwardly extending beams; and means for interlocking said outwardly extending beams with said wall.
14. A wave resisting unit, comprising a solid wall consisting of concrete H beams, superposed with their flanges arranged vertically edge to edge; outwardly extending courses of concrete H beams having their flanges arranged vertically, the inner ends of the beams of each course being interposed

between alternate beams in said wall, the beams of the wall being staggered to provide openings to receive said outwardly extending beams; and tie bolts extending vertically through the webs of alternate beams in said wall and the webs of the beams in said outwardly extending courses.

15. In a wave resisting structure; a wall composed of concrete H beams superposed with their flanges edge to edge, and held in alinement by means of positioners fitting within the opposed channels of said beams.

16. In a wave resisting structure, a wall consisting of concrete H beams superposed with their flanges edge to edge; positioners interposed between said superposed beams and fitted within the opposed channels thereof; and vertical tie bolts passing through the webs of said beams from the top to the bottom of said wall.

17. A wave resisting unit comprising a cribwork of crossed courses of concrete H beams, arranged with the webs thereof ver-

tically, said courses intersecting adjacent the ends of the beams thereof with the beams of one course alternating with those of the intersecting course; means for interlocking said crossed beams; and headers between the intermediate portions of spaced beams in certain of said courses, said headers having upper and lower portions fitting within opposed channels in said beams and an intermediate portion fitting between the edges of the opposed flanges of said beams.

18. A wave resisting unit, comprising a solid wall built up of H beams superposed with their flanges resting upon one another and disposed vertically and positioners interposed between said beams and fitting in the opposed channels thereof; and an open cribwork of crossed H beams interlocked with said wall and extending from one face thereof.

Signed by me this 12th day of July, 1922.

WILLIAM H. EVERSON.
